(57) **CLAIM**

The ornamental design for a scoop, as shown and described.

DESCRIPTION

FIG. 1 is an oblique view of a first variant of a scoop showing my new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side elevation view thereof; and

FIG. 7 is a right side elevation view thereof.

FIG. 8 is an oblique view of a second variant which corresponds to the scoop of FIG. 1 in an unfolded state;

FIG. 9 is a top plan view thereof;

FIG. 10 is a bottom plan view thereof;

FIG. 11 is a front elevation view thereof;

FIG. 12 is a rear elevation view thereof;

FIG. 13 is a left side elevation view thereof; and

FIG. 14 is a right side elevation view thereof.

The broken lines represent fold lines that form no part of the claimed design.

1 Claim, 10 Drawing Sheets
